UNITED STATES PATENT OFFICE.

WARREN A. RAMSAY, OF JERSEY CITY, NEW JERSEY.

WATERPROOF CONTAINER.

Application filed November 19, 1926. Serial No. 149,413.

This invention relates to improvements in water-proof containers and has particular reference to a container for carrying cigarettes, matches, and valuables by bathers while 5 in the water.

The primary object of the invention resides in a waterproof container adapted to be carried on the bathing belt of a bather, without fear of water entering the container, as the 10 same is provided with a captive cover which firmly seats on the body to seal the joint there-between.

Another object of the invention resides in a waterproof container which may be easily 15 attached to the bathing belt of a bather, and which container is of such shape and size as not to interfere with the body movements of the bather while bathing or swimming.

A further object of the invention is to provide a waterproof container having a removable captive cover which may be quickly moved to an open position when access to the interior of the container is desired.

With these and other objects in view, the 25 invention resides in certain novel construction and combination and arrangement of parts, the essential features of which are hereinafter fully described, are particularly pointed out in the appended claims and are illustrated in the accompanying drawing, in which:—

Figure 1 is a perspective view of my improved waterproof container.

Figure 2 is a vertical sectional view there- 35 through showing the cover in open position in dotted lines.

Figure 3 is a horizontal sectional view on the line 3—3 of Figure 2.

Referring more particularly to the drawing, the reference numeral 10 designates my 40 improved container in its entirety and which includes a hollow body 11 constructed of any suitable material which is closed at its top by a removable cover 12. The body is semi- 45 circular in cross section to provide a flat side 13 which fits against the belt 14 to which it is attached by reason of threaded studs 15 ex- 50 tending therefrom, and which pierce the belt and receive the clamping nuts 16 which are 55 screwed tight against the belt to firmly hold the container thereon. One of the nuts is provided with a spanner 17 for use in securely tightening the other nut by inserting the spanner in spanner recess 18 provided in said 60 other nut. The top edge of the body is pro- 65 vided with a bevelled seat 19 for co-acting

engagement with the rubber gasket 20 held by crimping the peripheral edge of the cover 12.

Extending approximately the entire length of the body and mounted centrally therein is 60 a sleeve 21 which is square in cross section for slidably receiving a squared block 22 which block has its lower end provided with a threaded recess 23 for threading engagement with the free end of a rod 24 fixed to a 65 bottom member or head 25, similar in shape to the cover 12 and which co-acts with the cover to give the container a rounded appearance at opposite ends. Provided on the top of the block 22 is a ball 26 for reception in a 70 socket 27 provided in the lower end of a shank 28 which extends from inside of the cover 12. From the foregoing description, it will be seen that when the cover is seated on the top of the body and the threaded end of the rod 24 screwed tight into the recess 23 the 75 cover and the bottom section 25 will be brought tight against the opposite ends of the body. Should it be desired to remove the cover to gain access to the interior of the body 80 the member 25 is turned to unscrew the rod 24 which relieves the tension on the cover thereby permitting the cover to be rotated and swung back without becoming separated from the body, due to the ball and socket connection. When the rod 24 is unscrewed, the lower member 25 will drop away from the bottom 85 whereupon the cover 12 is free to be lifted from its seat and turned with respect to the body to permit access to the interior of the 90 body.

For sealing the sleeve 21 at the bottom of the body, I provide the rod 24 with a washer 95 30, which engages the bottom of the body when the member 25 is tight against the body to prevent water from seeping through the joint between the member 25 and the body and into the body through the sleeve 21. For preventing accidental turning of the bottom section, the spanner 17 is moved to a position 100 100 to overlap the joint between the body and the bottom section.

It will be seen that when the cover is securely clamped down upon the body, no water can enter the interior of the body and any 105 articles such as cigarettes, matches or valuables contained therein will remain dry at all times, which allows the container to be worn in the water.

The container is so designed as to eliminate 110 any sharp corners which might injure a person should their skin come in contact there-

with, and to lie flat against the waist of a wearer when the belt is in a worn position.

While I have described what I deem to be the most desirable embodiment of my invention, it is obvious that many of the details may be varied without in any way departing from the spirit of my invention, and I do not limit myself to the exact details of construction herein set forth nor to anything less than the whole of my invention limited only by the appended claims.

What is claimed as new is:—

1. A watertight container comprising a hollow body open at its top, a sleeve rising from the bottom of said body, a block slideable within said sleeve, a rod extending through said sleeve and threaded to said block, said rod having a member fixed thereon for engagement with the bottom of said body, a cover for sealing engagement with the open end of said body, a ball provided on the top end of said block and a shank depending from

said cover and having a socket on the free end thereof for the reception of said ball.

2. A watertight container comprising a body open at its top and closed at its bottom, a sleeve rising from the bottom of said body, a block slideable within said sleeve, a rod extending through said sleeve and threaded to said block, said rod having a member fixed thereon for engagement with the bottom of said body, a washer on said rod for engagement with the bottom of said body for sealing the joint between said rod and said sleeve, a cover for sealing engagement with the open end of said body, a ball provided on the top end of said block, and a shank depending from said cover and having a socket on the free end thereof for the reception of said ball, substantially as and for the purpose specified.

In testimony whereof I have affixed my signature.

WARREN A. RAMSAY.
